UNITED STATES PATENT OFFICE

PHILIP G. COLE, OF IRVINGTON-ON-THE-HUDSON, NEW YORK

ICE SKATE WALKER

Application filed March 19, 1932. Serial No. 599,895.

The present invention relates to what I term an ice skate walker, and aims to provide certain improvements therein.

In ice skating it most frequently happens that the skating pond is located some distance from the club house, hotel, or other shelter from which the skater starts, and hence the skater is confronted with the dilemma of either putting on his skates at the pond and undergoing its attendant inconveniences, such as changing shoes, exposing the feet to the cold, checking his walking shoes, etc., or else of making the change at the hotel, shelter, or the like, and walking therefrom to the pond on his skate blades, thus subjecting the same to the dulling action resulting from repeated contact with the ground, to say nothing of the strain upon the ankles of the skater.

According to my present invention, I overcome the aforementioned objections and inconveniences by providing a skate walker or attachment having a blade protector and a walking tread, which devices can be quickly and easily attached and removed from the skates after the latter are put on by the skater. More specifically, my ice skate walker comprises a supporting tread and a blade gripper which may be manually or automatically operable to grip and positively hold on to the skate, said gripping means being preferably in the form of one or more resilient elements or a resiliently mounted rigid element.

My invention also embodies other features of novelty, and will be better understood from the detailed description which follows when considered in conjunction with the accompanying drawings, wherein—

Figure 1 is a side elevation of my skate walker attached to an ice skate.

Fig. 2 is a top plan view of the skate walker shown in Fig. 1, the skate blade being shown in cross section.

Fig. 3 is a transverse section taken substantially along the line 3—3 of Fig. 2.

Figs. 4, 5 and 6 are top plan views of other embodiments of my invention.

Fig. 7 is a section taken substantially along the plane of the line 7—7 of Fig. 6.

Referring first to Figs. 1 to 3 of the draw-

ings, my skate walker may be said to comprise a sole or tread portion A which supports on its upper side in proximity to the longitudinal center line thereof, a longitudinally extending rigid rib or abutment B having a flat vertical side wall b against which the blade C of a skate D may be engaged and clamped by suitable clamping means E.

The tread portion A may be formed of any rigid or semi-rigid material, and in outline approximates the sole of a moccasin, the under side of said tread portion being roughened, as indicated at a, so as to provide a good gripping engagement upon a slippery surface. Preferably, the skate walker will be formed of aluminum or an aluminum alloy by die casting or the like, the rib B being cast or integrally formed with the tread portion and braced in relation thereto by transverse ribs b'. Adjacent the flat vertical side b of the rib B there is provided a lateral supporting surface a' for the bottom of the skate blade, which surface a', if desired, may be grooved and fitted with a piece of felt, leather, packing, or the like, a², against which the bottom of the skate blade will bear and be protected from injury. In order that the skate blade may be positioned centrally of the skate walker, it will be apparent that the rib B must be disposed slightly to one side of the longitudinal center line of the tread portion.

The clamping means E is preferably designed to extend longitudinally of the rib in spaced relation thereto and normally disposed on the opposite side of the longitudinal center line of the tread portion and adapted for lateral movement with relation to the rib, so that the blade of the skate may be clamped between said rib and said clamping means.

In Figs. 1 to 3 the clamping means E is in the form of a rigid bar of metal bent into sinuous form, having nodes e intermediate its ends, which latter are reversely bent to provide U-shaped portions e'. The sinuous clamping bar E is supported on its lower edge upon the surface a' and the end portions e' thereof engage around a second longitudinally extending rib F mounted upon the tread portion A and reinforced by an up-

standing rib a^8 . To the free end of each of the U-shaped portions e' there is secured, as by riveting, or the like, a flat leaf spring G, which presses against the outer wall of the rib F, and normally tends to urge the clamping bar E away from the wall b . To hold the bar E in assembled relation upon the skate walker between the ribs B and F, one end of the said rib F is undercut, as indicated at f , to accommodate the bight of one U-shaped portion e' , and at the other end of said rib there is provided a removable cleat or lug f' designed to overlie the bight of the U-shaped portion e' at the opposite end of the bar E.

For laterally moving the bar E toward the rib B and into clamping engagement with the skate blade C, I provide a manually controlled lever H, one end of which is flattened, as indicated at h , and provided with a cam edge surface h' , adapted for movement through a horizontal slot f^2 in the rib F, said flattened end being pivotally mounted upon the rib a^8 , which is bifurcated by having the slot f^2 passing therethrough.

By manually moving the lever H from its position shown in Fig. 2 to that shown in Fig. 1, it will be apparent that the cam surface h' will engage the central portion of the sinuous clamping bar E and move the latter bodily toward the rib B to clamp the skate blade C between said rib and said clamping bar. It will also be apparent that skate blades of different thicknesses will be equally well held by the clamping bar, since immediately upon the clamping bar engaging the ice skate blade, the leaf springs G will flex as the operating handle is moved to its position shown in Fig. 1. The tension of the springs G will also function to hold the clamping lever in clamping engagement against accidental disengagement. To remove the skate walker from the ice skate blade, it is merely necessary to reverse the movement of the cam lever H, whereupon the clamping member will disengage the blade.

In the embodiment of my invention shown in Fig. 4, the tread portion A' is interiorly cut out, as shown at a^4 and a^5 , to substantially reduce the weight thereof, and the manually controlled cam lever J, instead of being pivotally mounted, is herein shown as being slidably mounted within the slot f^2 . One end of the lever J is laterally bent, as indicated at j , to extend through the slot f^2 and the other end is bent to provide a cam surface j' . For cooperative engagement with the cam surface j' of the lever, the clamping bar E', which in all other respects is similar to the bar E, is provided with a cam surface e^2 intermediate its ends. In the operation of this device the lever J, when moved from the right to the left, will function to cam the clamping bar E' into gripping engagement with a skate blade,

and when moved to the left, it will cause disengagement of such blade.

In the embodiment of my invention shown in Fig. 5 the clamping means are in the nature of a plurality of powerful leaf springs K and L, suitably mounted upon anchorages k and l , and having portions thereof, k' , l' and l^2 , normally pressing against the flat side wall b of the rib B. In applying this form of skate walker to a skate, the blade of the latter may be longitudinally inserted between the clamping means and the rib B from either end of the device, in the course of which action the springs K and L will flex and the portions k' , l' and l^2 will engage the side of the blade and clamp it against the rib B. To facilitate the entrance of the skate blade from either end of the device past the spring ends k' and l^2 , the latter are curved away from the rib B, as shown at k^2 and l^3 , respectively.

In the modification shown in Figs. 6 and 7, the construction of the clamping means is somewhat analogous to that shown in Figs. 1 to 3, except that the sinuous clamping bar M is formed of resilient metal, and hence the supplemental springs G of Figs. 1 to 3 are dispensed with. For moving said spring bar M, it has fastened to it midway its ends a collar m which extends through the slot f^2 in rib F, said collar having an opening m' therein. Also extending through the slot f^2 and pivotally mounted upon a pin n between the bifurcations of the rib a^8 is one end of an operating lever N, similar to the lever H, having a cam surface n' adapted to engage and move the spring bar toward the rib B. The pin n extends through the opening m' in the collar m, as does also a pin n^2 on the lever N, said pin n^2 functioning to withdraw the spring bar M when the movement of the lever N is reversed by engaging against the curved wall m^2 of the opening m' .

While I have shown and described several embodiments of my invention, it is to be understood that I do not desire to be limited to the specific details of the constructions shown, since the same may be varied or modified without departing from the spirit of the invention.

What I claim is:

1. A skate walker or the like, comprising a sole or tread portion, a longitudinally extending abutment supported on the upper side of the tread portion and in proximity to the longitudinal center line thereof, and clamping means mounted on the tread portion and extending longitudinally of the abutment for lateral movement with relation thereto for clamping therebetween the blade of an ice skate.

2. A skate walker or the like comprising a sole or tread portion, a longitudinally extending rigid rib supported on the upper side of the tread portion and slightly to one side of the longitudinal center line thereof, and

a clamping member mounted on the tread portion and extending longitudinally of the rib and normally disposed on the opposite side of the longitudinal center line of the tread portion, said clamping member being movable laterally with relation to the rib for clamping therebetween the blade of an ice skate.

3. A skate walker or the like comprising
10 a sole or tread portion, a longitudinally extending rigid rib having a flat vertical side and supported on the upper side of the tread portion and slightly to one side of the longitudinal center line thereof, and a clamping
15 member mounted on the tread portion and extending longitudinally of the rib and normally disposed on the opposite side of the longitudinal center line of the tread portion, said clamping member being of sinuous form
20 having a substantially flat vertical side wall for lateral movement with relation to the rib for clamping therebetween the blade of an ice skate.

4. A skate walker according to claim 1,
25 wherein the clamping means are resiliently mounted.

5. A skate walker according to claim 1,
wherein the clamping means are resiliently mounted, and manually operable means are
30 provided for laterally moving the clamping means.

6. A skate walker according to claim 1,
wherein the clamping means are resiliently mounted, and a manually controlled cam
35 lever is provided for laterally moving the clamping means.

7. A skate walker or the like comprising
a sole or tread portion, a longitudinally extending rigid rib having a flat vertical side
40 and supported on the upper side of the tread portion and somewhat to one side of the longitudinal center line thereof, and another rib mounted on the tread portion somewhat to the opposite side of said center line thereof
45 and substantially parallel to the first rib, and a clamping member disposed between said ribs and supported by the second rib.

8. A skate walker or the like comprising
a sole or tread portion, a longitudinally extending rigid rib having a flat vertical side
50 and supported on the upper side of the tread portion and somewhat to one side of the longitudinal center line thereof, and another rib mounted on the tread portion somewhat to the opposite side of said center line thereof
55 and substantially parallel to the first rib, a clamping member disposed between said ribs and supported by the second rib, and manually operable means extending through an
60 opening in said second rib for moving the clamping member into clamping engagement.

In witness whereof, I have hereunto signed
my name.

PHILIP G. COLE.
